2 SHEETS—SHEET 2.

UNITED STATES PATENT OFFICE.

ALBERT K. GULHAUG, OF WOLF POINT, MONTANA.

PHOTOGRAPHIC-PRINTING FRAME.

1,363,410.

Specification of Letters Patent. Patented Dec. 28, 1920.

Application filed October 24, 1919. Serial No. 332,951.

To all whom it may concern:

Be it known that I, ALBERT K. GULHAUG, a citizen of the United States, residing at Wolf Point, in the county of Roosevelt and

5 State of Montana, have invented certain new and useful Improvements in Photographic-Printing Frames, of which the following is a specification, reference being had to the accompanying drawings.

10 This invention relates to the art of photography, and particularly to printing frames.

The general object of my invention is the provision of a frame which is adapted to be 15 used in connection with any of the standard photographic printing machines now on the market, but which is particularly adapted for the printing of film negatives.

More specifically, the object of the invention 20 is to provide a construction of this character which is particularly adapted for the printing of film negatives in which the separate pictures have not been cut apart.

And a further object is to provide a device 25 of this character which is adjustable so that negatives of any size within a certain range may be printed, the device having a large range of adjustment.

A further object in this connection is to 30 provide a printing frame which will print negatives of any size within a certain range and in which the print will have a white border surrounding the printed portion of the picture, this white border being secured 35 without the necessity of any mask.

A further object is to provide a machine 40 of this character which will handle and secure proper prints from negatives which are warped or curled, and more specifically provide a machine which will flatten the warped or curled negative and hold it in proper position without the necessity of adjusting or flattening this curled negative while the paper is being put in place.

45 Other objects will appear in the course of the following description.

My invention is illustrated in the accompanying drawings, wherein:—

Figure 1 is a perspective view of a printing frame constructed in accordance with 50 my invention, the back or cover being shown as lifted;

Fig. 2 is a sectional view through the frames A and B and extending from front 55 to rear;

Fig. 3 is a transverse sectional view on the line 3—3 of Fig. 2;

Fig. 4 is a perspective view of the means for locking the clamp 24;

Fig. 5 is a plan view of the frame B;

Fig. 6 is a fragmentary side elevation of one side bar of frame A;

Referring to these drawings, it will be seen that I provide what I may term a main frame, designated generally A, and a slide- 60

able negative supporting frame, designated generally B. The frame A includes two longitudinally extending side members 10 and a transversely extending cross member 11.

One of the side members 10 is longitudinally slotted, as at 12, this slot extending from the end of the side member remote 70

from the cross bar 11 toward said cross bar 11 to about the middle of the frame. The

opposite side member 10 has only a relatively short slot 12^a and the remainder of the upper portion of the side member is cut away so as to leave simply a support 10^a 75

extending beneath the frame B. The extremity of this supporting member 10^a is 80 formed with a rotatable catch 13, while pivoted to the extremity of the upper wall of slot 12 of member 10 is a catch 14.

The frame B is rectangular in form and has longitudinal bars 15, and the end bars 85

16 which extend upward above the longitudinal bars in a manner which will be obvious from the drawings. The bars 15 and 16 are rabbeted or otherwise formed, as at 17, to

provide a seat for a sheet of glass 18. This 90

sheet of glass is partially covered by a sheet of opaque material 19 as, for instance, black paper, paint, or any other suitable material, this opaque portion of the sheet 18 being

formed to extend across one end of the sheet 95 and along one side of the sheet. The width of the frame B is equal to the depth of the slot 12 so that when the frame is in place, it is disposed entirely within the slot 12 and

extends into the slot 12^a and rests upon the 100 member 10^a in a manner which will be obvious from Fig. 1. When in place, it is held by the catches 13 and 14. This frame is

slidable transversely in the slots 12 and 12^a. The side bars 10 of the main frame A 105 have, at their rear ends, the inwardly projecting, metallic strips 26, these side bars on their inner faces being rabbeted below the strips, as at 21, rearward of the slots 12 and 12^a. The side bars and end bars are formed 110

with inwardly extending ledges 22 whose upper faces are flush with the upper face of the rear longitudinal bar 15 of frame B. Disposed within the frame A for removal 5 therefrom and adjustment thereon is the slide 23. Hinged to this slide is an L-shaped clamp 24 which is hinged to the slide, as at 25. Attached to the outer faces of the clamp 24 is a metallic strip, angular 10 in cross section, so as to provide an outwardly projecting flange 27. In order to hold this clamp down in its operative position, I provide on the slide 23 an upwardly projecting bracket 28 and on the extremity 15 of the clamp 24 an upwardly projecting bracket 29. Pivoted to the bracket 28 is a longitudinally slotted arm 30, and pivoted to the bracket 29 is an arm 31, the extremity 20 of which extends into the slot of the arm 30 and is pivoted thereto, as at 32. The arm 30 is provided with a laterally projecting finger piece 33.

It will be obvious now that when the finger piece is depressed, the arms 30 and 31 25 will be brought into alignment and this will hold the clamp 24 depressed against any raising movement, because the finger piece 33 will extend over the rod or arm 31 and prevent any upward movement of the two 30 sections of the clamp. When, however, the finger piece 33 is raised, the arms will be brought into angular relation, which will 35 raise the clamp 24. This clamp 24, and specifically the flange 27, is designed for the purpose of clamping a film down tightly upon the glass plate 18.

For the purpose of holding a sheet of printing paper against the negative, I provide the sectional lid or cover formed in two 40 parts 34 and 35. The part 34 is hinged by strap hinges 36 to the slide 23 and the part 35 is hinged to the part 34 by hinges 37 so that the part 35 will break upwardly independent of the part 34, but the parts 34 and 45 35 together may be moved bodily upward by means of the hinges 36. A handle may be applied to the part 34 whereby the two sections of the lid or cover may be raised or lowered together, and the handle may be 50 also applied to the section 35 whereby it may be independently raised if desired. The inner face of the sections 34 and 35 are preferably lined with felt.

For the purpose of holding the slide 23 in 55 adjusted positions within the frame A, I provide a transversely extending clamping rod 38 which is rotatably mounted upon the upper face of the slide and which is cranked at its ends, as at 39, and provided with a 60 radially extending handle 40. When this handle is rotated in one direction and down against the slide, the cranked portion 39 of the clamping rod will be turned so as to bear upward against the inner faces of the strips

26 thus forcing the slide down against the 65 seat 22 in the frame A and holding it firmly in position wherever it is adjusted. When the handle 40 is turned upward, the clamp 70 will be released and then the slide with its back sections 34 and 35 may be shifted to any desired position within the frame A.

In the use of this device, the frame B is shifted transversely in the frame A so that the exposed transparent portion of the glass plate 18 will be slightly less than the length 75 of the negative or less than the length of a single picture in a strip of negatives. Then the slide 23 is adjusted in the frame A so that when the clamp 24 is turned down, the flange 27 will overlap one longitudinal edge 80 and one end edge of the negative. It will be obvious now that that portion of the glass 85 18 which is exposed and which is transparent will be slightly less than the size of the negative. The clamp 24 is then raised and the negative disposed in place upon the plate 18. If a strip of negatives are to be printed, then the end of the strip is forced through the slot 12 and carried beneath the clamp. Then the clamp is turned downward, thus 90 flattening the negative and holding it firmly in place upon the glass 18. The printing paper is then disposed upon the face of the negative, it being centered by engagement 95 against the right angular faces of the clamp 24 and resting upon the flange 27 and then the back sections 34 and 35 are brought downward and held down by hand or other suitable means until the picture is printed. As many prints are made as desired, and 100 then the clamp 24 is released and a new negative disposed in place and the printing is continued.

With this device, negatives of different sizes may be printed very quickly by a very 105 simple adjustment, or a series of negatives of the same size may be readily printed after one adjustment. Each of these prints will have a white border about $\frac{1}{4}$ of an inch wide, the flange 27 acting as a mask for two sides 110 of the negative, while the opaque portion 19 acts as a mask for the other two sides of the negative. It will be seen that kodak 115 films of any length can be printed without first cutting apart by placing the end of the film through the slot 12 and simply feeding the film forward. No matter how curly or warped the film negative may be, it will be flattened down against the glass sheet 18 and held firmly in position by the film 120 clamp 24 with its flange 27. Of course, it is 125 obvious that this printing frame may be made in various sizes and have either a relatively small range of adjustment or a relatively large range of adjustment as desired.

While I have illustrated certain details of construction and arrangement of parts, I do not wish to be limited to these, as it is ob-

vious that many modifications might be made in these details without departing from the spirit of the invention.

I claim:—

5 1. A photographic printing frame including a rectangular frame supporting a glass sheet, the glass sheet having an opaque portion extending across one end thereof and longitudinally along one side thereof to define a rectangular, transparent portion, a second frame through which the first frame is transversely adjustable, a slide mounted on the second frame for adjustment thereon at right angles to the direction of movement 10 of the first named frame, an L-shaped clamp hinged to said slide for movement toward and away from the plane of the glass sheet, and a sectional back hinged to the slide and filling the space defined by the L-shaped 15 clamp and movable toward or away from the plane of the glass.

2. A photographic printing frame including a rectangular frame supporting a glass sheet, the glass sheet having an opaque portion extending across one end thereof and longitudinally along one side thereof to define a rectangular, transparent portion, a second frame through which the first frame is transversely adjustable, a slide mounted 20 on the second frame for adjustment thereon at right angles to the direction of movement of the first named frame, an L-shaped clamp hinged to said slide for movement toward and away from the plane 25 of the glass sheet, a thin flange projecting outward from the L-shaped clamp and bordering the space defined by said clamp, and a sectional back hinged to the slide for movement toward and away from the plane 30 of the glass and adapted to fill the space defined by said clamp and to rest against said flanges of the clamp.

3. A photographic printing frame including a rectangular frame supporting a glass sheet, the glass sheet having an opaque portion extending across one end thereof and longitudinally along one side thereof to define a rectangular, transparent portion, a second frame through which the first frame is transversely adjustable, a slide mounted on the second frame for adjustment thereon at right angles to the direction of movement of the first named frame, an L-shaped clamp hinged to said slide 45 for movement toward and away from the plane of the glass sheet, a thin flange projecting outward from the L-shaped clamp and bordering the space defined by said clamp, a sectional back hinged to the slide for movement toward and away from the plane of the glass and adapted to fill the space defined by said 50 clamp and to rest against said flanges of the clamp, means for locking the slide in adjusted positions, and

means for locking the clamp in a depressed 65 position.

4. A photographic printing frame including a rectangular frame supporting a glass sheet, the glass sheet having an opaque portion extending across one end thereof and longitudinally along one side thereof to define a rectangular, transparent portion, a second frame through which the first frame is transversely adjustable, a slide mounted on the second frame for adjustment 70 thereon at right angles to the direction of movement of the first named frame, an L-shaped clamp hinged to said slide for movement toward and away from the plane of the glass sheet, a thin flange projecting 75 outward from the L-shaped clamp and bordering the space defined by said clamp, a sectional back hinged to the slide for movement toward and away from the plane of the glass and adapted to fill the space 80 defined by said clamp and to rest against said flanges of the clamp, means for locking the slide in adjusted positions, and means for locking the clamp in a depressed position, said last named means including arms 85 pivotally connected to the back and clamp respectively and to each other, one of said arms projecting beyond the other arm and having a laterally extending thumb piece 90 extending over the plane of the other arm 95

5. A photographic printing frame including a rectangular frame supporting a glass sheet, the glass sheet having an opaque portion extending across one end thereof and longitudinally along one side thereof to define a rectangular, transparent portion, a second frame through which the first frame is transversely adjustable, a slide mounted on the second frame for adjustment thereon at right angles to the direction of movement of the first named frame, an L-shaped clamp hinged to said slide for movement toward and away from the plane of the glass sheet, a thin flange projecting outward from the L-shaped clamp and bordering the space 100 defined by said clamp, a sectional back hinged to the slide for movement toward and away from the plane of the glass and adapted to fill the space defined by said clamp and to rest against said flanges of the clamp, means for locking the slide in adjusted positions, and means for locking the clamp in a depressed position, the first named clamp comprising a transversely extending rotatable rod cranked at its ends and having a handle, the second named frame having inwardly extending, parallel flanges on its side beneath which said crank-shaped portions of the rod are adapted to engage. 110

6. A photographic printing frame including a rectangular frame rabbeted to receive a glass sheet, a sheet of glass disposed in 115 120 125

said frame and having an opaque portion extending transversely across the glass and longitudinally of the glass, a second frame having a cross bar, two parallel side portions, both of said side portions being slotted to receive the first named frame, the first named frame having a length greater than the width of the second named frame, whereby the first named frame may be longitudinally adjusted within the second named frame, a slide mounted in the second named frame for adjustment at right angles to the direction of adjustment of the first named frame, an L-shaped film clamp hinged to said slide and having its inner margins formed with inwardly projecting, relatively thin flanges, means for holding said L-shaped clamp depressed against the face of the glass or in a raised position, and a back hinged to the slide and adapted to fill the space defined by said clamp and rest upon said flanges.

7. A photographic printing frame including a rectangular frame supporting a glass sheet, a second frame in which the first frame is transversely adjustable, a slide mounted on the second frame for adjustment thereon at right angles to the movement of the first named frame, a film clamp hinged to the slide for movement into position against the glass sheet, and a back section hinged to the slide for movement toward and away from the plane of the glass.

8. A photographic printing frame including a rectangular frame supporting a glass sheet, a second frame in which the first named frame is transversely adjustable, a slide mounted on the second named frame for adjustment thereon at right angles to

the movement of the first named frame, a film clamp hinged to the slide for movement toward and away from the plane of the glass and including a relatively thin, inwardly projecting flange, and a back section hinged to the slide for movement toward and away from the plane of the glass and fitting within the film clamp and adapted to rest upon the upper face of said flange.

9. A photographic printing frame including a transparent negative support, a hingedly mounted film clamp having a relatively thin film engaging flange, the clamp being adjustable as a whole in a plane parallel to the face of the negative support and being oscillatably shiftable toward and from the transparent support, and a hingedly supported back section adapted to engage the paper to be printed and fitting within the film clamp and adapted to rest upon the upper face of the flange thereof.

10. A photographic printing frame including a rectangular frame having its side slotted, a second rectangular frame supporting a glass sheet and disposed within the slots of the first named frame and transversely adjustable therethrough, a slide carried on the first named frame for adjustment thereon at right angles to the line of movement of the second named frame and having a hinged section angular in plan and having a film clamping flange on its edge face, and a back section hinged to the slide for movement toward and away from the plane of the glass and fitting within said angular hinged section when closed.

In testimony whereof I hereunto affix my signature.

ALBERT K. GULHAUG.
